Kevin Prince(57) **CLAIM**

We claim the ornamental design for a wheel center cap, as shown and described.

DESCRIPTION

FIG. 1 is a perspective view of a wheel center cap, showing our new design;

FIG. 2 is an enlarged, exploded perspective view thereof;
FIG. 3 is a top plan view thereof, the bottom plan view,
left-side elevational view, and right-side elevational view all
being identical thereto;

FIG. 4 is a front elevational view thereof;

FIG. 5 is a rear elevational view thereof; and,

FIG. 6 is a bottom perspective view thereof.

The broken lines showing a wheel in FIG. 1 and mounting
clips in FIGS. 1-3, 5 & 6 depict environmental matter and
form no part of the claimed design.**1 Claim, 2 Drawing Sheets**FIG. 1
